Inventor:

John L. Field

UNITED STATES PATENT OFFICE.

JOHN L. FIELD, OF SYRACUSE, NEW YORK.

METHOD OF STRAPPING WOOD IN BENDING.

Specification of Letters Patent No. 23,912, dated May 10, 1859.

To all whom it may concern:

Be it known that I, JOHN L. FIELD, of the city of Syracuse, in the county of Onondaga and State of New York, have invented a 5 new and useful Improvement in Devices for Bending Timber; and I do hereby declare the following to be a full, clear, and exact description of the construction and operation of the same, reference being had to the 10 annexed drawings, making part of this specification, in which—

Figure 1, represents a perspective view of a forming frame. Fig. 2, represents a metallic strap used for obtaining an endwise pressure upon the timber to be bent, and Fig. 15 3, represents a piece of timber bent into the form required for the rail of a carriage seat.

In Fig. (1) (A, A', A') are forming beds around which the timber is to be bent. (B) 20 is a firm body piece to which the beds are attached. (C, C) are projections for holding the keys (D, D). (E, E) are clamp hooks attached to the forming beds (A', A').

(F) is a piece of timber bent according to 25 the form shown in Fig. 1.

(G) is a metallic strap connected to the frame by the pin (H) having at its extremity the screw (I) by which an endwise pressure is made upon the timber before 30 bending. The strap laying upon the rounding or outer surface of the timber at the curve serves to bind the piece (F) firmly onto the form; also to prevent, by the endwise pressure of the screw, the grain of the 35 timber from breaking upon the outer surface, and shortens the grain upon the inner surface. Heretofore the metallic strap has

been used in the process of bending timber where only a single curve is obtained. The nature of my invention consists in a device 40 whereby the metallic strap after passing one curve upon a piece of timber may be connected with a strap placed upon another side of the same piece for the purpose of bending it in another direction, and thereby 45 continuing the endwise pressure through the various curves to which the piece may be subjected. This connection between the straps upon the different sides of the timber may be made by an angular set-off as shown 50 at (O), the straps being riveted or otherwise firmly fastened to the wings of the device. I do not desire to limit myself to this precise form of a setoff, but generally to any form of connection by which the strap and 55 pressure may be made continuous over the curves in different directions upon the same stick.

I do not claim to have invented the application of endwise pressure in the process of 60 bending timber, as it is in general use.

What I claim as my invention, and desire to secure by Letters Patent, is,

The method substantially as described of 65 connecting metallic straps for bending timber when the parts are so arranged as to operate in connection with the forming frames in the manner and for the purpose set forth.

JOHN L. FIELD.
